UNITED STATES PATENT OFFICE.

EARNEST FLORA, OF EDDYVILLE, KENTUCKY, ASSIGNOR OF ONE-HALF
TO CHARLES W. DORMAN, OF EDDYVILLE, KENTUCKY.

RAILWAY CROSS-TIE AND CLAMP.

SPECIFICATION forming part of Letters Patent No. 767,878, dated August 16, 1904.

Application filed April 13, 1904. Serial No. 202,959. (No model.)

To all whom it may concern:

Be it known that I, EARNEST FLORA, a citizen of the United States, residing at Eddyville, in the county of Lyon and State of Kentucky, have invented a new and useful Improvement in a Railway Cross-Tie and Clamp; of which the following is a specification.

This invention is an improved construction of railway cross-tie and clamp, the object being to provide an exceedingly strong and durable construction of metallic railway-tie and a simple and efficient form of rail-clamp adapted to be used in connection with the said rail-tie.

Another object of the invention is to provide a clamp which will securely hold the rail to the tie and completely avoid the use of spikes now commonly employed for the purpose of securing the rails to the ties.

With these objects in view the invention consists in the novel features of construction, combination, and arrangement, all of which will be fully described, and pointed out in the claims.

In the drawings forming a part of this specification, Figure 1 is a perspective view showing the practical application of my invention. Fig. 2 is a view showing the base and top sections of the cross-tie. Fig. 3 is a longitudinal sectional view of the tie and clamp complete. Fig. 4 is a transverse section on the line 4-4 of Fig. 3. Fig. 5 is a detail perspective view of one of the clamp members.

In carrying out my invention I employ a metal base-plate A, preferably made of wrought-iron and having a stop-shoulder A' at one end. Parallel guide-pieces A² are arranged upon the opposite sides of the base-plate at the opposite ends, the opposing faces of said guides being undercut, as shown at A³, thereby providing a dovetailed recess between the guide members.

B indicates the upper section of the cross-tie, and which is preferably made of steel. This upper section is cut away upon the opposite sides at the opposite ends, as shown at B', thereby providing dovetailed portions B², which are adapted to engage the undercut guide members A², and whereby the upper and

lower sections are securely locked together 50 when the upper section is slid into the lower or base section, as most clearly shown in Figs. 1, 3, and 4. The movement of the upper section is limited by the stop-shoulder A'. The central portion of the upper section B is reduced, as shown at B³, thereby saving metal 55 and imparting a certain amount of elasticity to the upper section. The rails C rest upon the upper sections B, and in order to securely fasten the rails to the said upper section I employ clamps D, the heads D' of which overlap the base-flanges of the rails, while the shanks D² enter openings E, produced in the bar B adjacent the opposite ends, laterally-projecting shoulders D³, formed at the juncture 60 of the head and shank, resting transversely across the opening E and upon the upper faces of the bar B. The lower end of the shank is also provided with laterally-projecting foot-pieces D⁴, which engage the inwardly-projecting 65 shoulders E', formed at the bottom openings E, said openings E being of a length to permit the lower end of the shank, with the feet D⁴, to be inserted longitudinally and then turned transversely, so as to bring the head 70 D', shoulders D³, and feet D⁴ into the positions shown in Fig. 4, and for the purpose of locking the clamps in this position I employ the wedge-blocks F, which are driven down into the opening E between the end of said opening 75 and the shank of the clamp, as most clearly shown in Fig. 3.

Owing to the construction of the clamp, it will be impossible for it to move upwardly, and consequently there will be no excessive 80 strain upon the wedge-blocks, and their only function will be to hold the clamps into their proper positions for clamping the base of the rail.

A combination cross-tie and rail-clamp constructed as herein shown and described will 85 securely hold the rail in its exact position, and there is no danger whatever of the said rail working loose upon the cross-tie, and said cross-tie being made of metal it will last an 90 indefinite time. However, whenever it is desired to remove the rail and replace it with another one it can be quickly and easily ac- 95

complished by withdrawing the wedge-blocks, sliding back the clamping members, and removing the rail. The new rail is then set in place, the clamp member moved up, and the 5 wedge inserted.

Having thus fully described my invention, what I claim as new, and desire to secure by Letters Patent, is—

1. A railway cross-tie comprising the base member having the undercut guides at the opposite sides adjacent the ends, and the top section having the dovetailed portions at the ends adapted to fit the undercut guides as set forth.
- 15 2. A railway cross-tie comprising a base having the undercut guides of the sides and a stop-shoulder at one end, and the top member having dovetailed portions upon the lower side at the opposite ends and adapted to engage 20 undercut guides of the base-section as set forth.

3. A device of the kind described comprising in combination the base-section having the undercut guides and the stop-shoulder, the top section having dovetailed portions upon the lower side at the ends and adapted to engage 25 the undercut guides, and means carried by the top section for clamping the sections as set forth.

4. The combination with the base-section having the undercut guides and the stop-shoulder, the top section having the dovetailed portions adapted to engage the undercut guides, said top section having openings adjacent each end, the clamps adapted to be arranged in the openings and the wedge-blocks 30 35 adapted to hold the clamps in place as set forth.

EARNEST FLORA.
